UNITED STATES PATENT OFFICE.

AUGUSTIN ALMA KING, OF FINCHLEY, ENGLAND.

ELECTRIC TORCH.

1,358,639.

Specification of Letters Patent.

Patented Nov. 9, 1920.

Application filed February 4, 1920. Serial No. 356,211.

To all whom it may concern:

Be it known that I, AUGUSTIN ALMA KING, a subject of the King of Great Britain, of 65 Lichfield Grove, Finchley, in the 5 county of Middlesex, England, have invented new and useful Improvements in and Relating to Electric Torches, of which the following is the specification.

This invention relates to electric torches 10 or pocket lamps of the type in which a freely movable ball switch is arranged in such a manner that it closes the circuit only when the lamp is inclined downwardly and breaks the circuit when an upward inclination is given to the lamp.

The present invention has for its primary 20 object to prevent the ball switch from opening the circuit when the torch is held perpendicularly to throw the light downwardly, the tendency being for the ball to make and break contact thus causing flickering or extinguishing of the light.

With the above object in view I house the ball in a chamber the wall of which is composed of metal and is fluted or corrugated 25 longitudinally and is slightly tapered toward one end which is open. This open end is closed by a metal disk forming the head of a cap which is insulated from the 30 wall of the ball chamber the latter being formed inside the cap which closes the end of the torch. The metal disk above referred to is formed with a concave or convex portion eccentric therewith and to the 35 opening of the ball chamber so that when the torch is held vertically with the lamp downward the ball enters the depression in the metal disk, or falls upon the dome, and is thereby caused to rest against the wall 40 of the ball chamber and maintain contact therewith. The metal disk of the cap closing the ball chamber is electrically connected with the battery either by a spring 45 interposed between the battery and said cap or by other suitable means.

In the accompanying drawings,

Figure 1 is a view in vertical section of 50 an electric torch embodying the present invention.

Fig. 2 is a sectional view on the line 2—2 in Fig. 1.

Fig. 3 is a view similar to Fig. 1 illustrating a modification and

Fig. 4 illustrates a further modification. 55 The torch comprises the usual battery 1,

case 2, lens 3, lamp 4 and switch 5 all of which are well-known.

For the purpose of my invention I provide the torch with a ball-switch *a* and house the latter in a conical casing *a'* composed of metal and the side wall of which is fluted or corrugated as shown in Fig. 2. The top of this casing is open but is covered by a disk *b* spaced therefrom and supported upon a ring *b'* composed of insulating material which forms a lining to a cap *c*. 65

The disk *b* is formed eccentrically with an indentation *b*² providing on the one side of the disk a concavity and on the other a convexity, either of which may be presented 70 toward the ball switch *a*.

The cap *c* incloses the casing *a'* and is attached to a base *c'* composed of insulating material to which the said cap is attached by means of tangs *c*², *c*² passed through slots 75 in the base *c'* and then bent over. One terminal of the device is provided by stud or bolt *c*³ attached to the bottom of the conical casing *a'* and the other terminal by a metal spring *d* which embraces the cap *c*. 80

The device assembled as above may be attached by means of the bolt *c*³ to the usual screw-cap 6 which closes the end of the case 2, the inner face of said screw-cap being provided with insulating material *c*⁴. Al- 85 ternatively the device may be interposed between two cells of the battery 1 as shown in Fig. 3; or the device may be placed between the battery 1 and the lamp 4 as shown in Fig. 4. 90

To insure ample contact surfaces being provided that face of the metal disk *b* presented toward the ball switch *a* is roughened by serrations, flutings or otherwise so as to form numerous projections so that the 95 ball switch makes contact at more than one point. With the same object the surface of the ball switch may be roughened.

With the above construction when the electric torch is held with the lamp 4 presented toward the ground the ball-switch *a* rests upon the disk *b* and owing to the indentation *b*² in the latter the switch is caused to remain eccentric with the disk *b* and to make contact with the side wall of the 100 casing *a'*. Assuming the switch 5 usually provided is closed a circuit is now established from the base of the battery 1, through the spring *d*, cap *c*, disk *b* ball switch *a*, conical casing *a'*, bolt *c*³, screw 105 110

cap 6, case 2, switch 5 and thence through the lamp 4 to the upper terminal of the battery 1. If now the torch is held with the lamp 4 presented in a horizontal direction 5 the ball-switch *a* rolls away from the disk *b* and breaks the circuit between the said disk and the conical casing *a'*.

The improved torch is particularly useful for employment in cinemas and theaters 10 when it is dark for showing people to their seats without flashing the light into the faces of those seated, the lamp circuit being automatically broken when the lamp is raised.

What I claim as my invention and desire 15 to secure by Letters Patent is:—

In an electric torch furnished with a bat-

tery the provision of an automatic switch comprising a freely movable metal ball housed in a conical metal casing open at the top and the side wall of which is corrugated, 20 a metal disk covering said metal casing and having formed eccentrically therewith an indentation, means for insulating said disk from said conical casing, a metal cap inclosing said disk and casing, a base composed 25 of insulating material to which said cap is secured and terminals attached to said cap and said conical casing respectively, substantially as herein described.

Dated this fourteenth day of January, 30 1920.

AUGUSTIN ALMA KING.
